UNITED STATES PATENT OFFICE

123,829

DESIGN FOR A HANDLE FOR KITCHEN UTENSILS OR SIMILAR ARTICLES

William A. Beck, Chicago, Ill., assignor to The Edward Katzinger Company, Chicago, Ill., a corporation of Illinois

Application April 19, 1940, Serial No. 91,766

Term of patent 7 years

To all whom it may concern:

Be it known that I, William A. Beck, a citizen of the United States, residing at Chicago, in the county of Cook and State of Illinois, have invented a new, original, and ornamental Design for a Handle for Kitchen Utensils or Similar Articles, of which the following is a specification, reference being had to the accompanying drawing, forming a part thereof.

Fig. 1 is a side elevational view of a handle
for kitchen utensils or similar articles, showing
my new design.

Fig. 2 is a similar view with the handle turned through an angle of 90°.

Fig. 3 is a rear end elevational view of the same.

I claim:

The ornamental design for a handle for kitchen utensils or similar articles, substantially as shown.

WILLIAM A. BECK.
